UNITED STATES PATENT OFFICE.

BERNARD BRIODY, OF YOUNGSTOWN, OHIO, ASSIGNOR TO TRUSCON STEEL COMPANY,
OF YOUNGSTOWN, OHIO, A CORPORATION OF MICHIGAN.

REENFORCED CONCRETE ROADWAY.

Application filed March 24, 1924. Serial No. 701,282.

This invention relates to the construction of concrete roadways, and its object is to so reinforce the roadway as to prevent the corners and edges of the panels of the roadway being broken by the wheels of the enormously heavy freight trucks which are now employed to transport merchandise over such roadways. 5

It has been observed that when a crack forms in a concrete roadway because of the 10 upheaval of the earth or because of shrinkage, that the corners of the panels thus formed are often broken by the wheels of heavy vehicles.

The reason is that concrete has comparatively little tensile strength and is thus poorly 15 adapted as material for cantilevers unless reinforced. The edges and corners of panels or slabs of concrete roadways are often insufficiently supported because of the softness or unevenness of the earth beneath them and so 20 when an excessive load comes onto such edge or corner it is broken off, leaving another corner subject to similar damage. That this is so can be observed by the patching necessary along the edges of concrete roadways where 25 substantially triangular replacements are common.

My present invention consists in a proper metal reenforcement extending along the edges of the roadway and also transversely 30 thereto at each side of the lines where cracks are predetermined so that the breaking off of the edges and corners may be prevented. In order to insure that the roadways when they do crack will crack along predetermined lines, 35 strips or plates of sheet metal placed on edge are positioned along the lines where the cracks are to occur.

This invention is illustrated in the accompanying drawing, wherein Fig. 1 is a diagrammatic plan of a roadway provided with 40 my improved dividing plates and reenforcements. Fig. 2 is a section on the line 2—2 of Fig. 1 on a larger scale. Fig. 3 is a side elevation and Fig. 4 is a plan of a bar adapted 45 for reenforcing the edges of panels of roadways.

Similar reference characters refer to like parts throughout the several views.

The roadway 1 is shown divided into panels 50 by means of the dividing plates 2 which are longitudinally corrugated or channelled so as to produce dowel grooves and tongues in

the edges of adjacent panels. These plates do not extend to the finished surface of the roadway and therefore do not cause or constitute objectionable ridges, but they control the lines of cracks which usually form where the concrete contracts or when the foundations heave up during freezing weather. The dowel construction causes the adjacent edges 55 of the panels to come down together, the pins 3, if used, assisting in this work. This construction alone forms no part of the present invention.

In order to prevent the corners which are 60 produced when the slab cracks along the dividing plates, truss bars 4 may be embedded along the edges of the panels, and I prefer to employ the well known Kahn bars which have square central portions 6, lateral 70 flanges 7 and tongues or shear members 8 formed therefrom. I prefer these shear members to have their ends 9 bent back to constitute anchors and the tongues on opposite sides of the central portion 6 inclined in 75 opposite directions so as to secure truss action. This type of bar is of proper form to reenforce the slab against an upward thrust of the foundation and against a downward pressure from a truck wheel. Whether the 80 shear members 8 extend upward or downward will be decided by the engineer in charge of construction, for the central portions 6 of the bars are tension members and should be embedded in the upper portion of the slab if 85 there is danger of the corners of the panels or the outer edges thereof being undermined, but if the greater danger is from upheaval caused by frost, the bars should be embedded as shown in Fig. 2. 90

The details of construction and the sizes and proportions of these reenforcing bars may all be changed by those skilled in the art without departing from the spirit of my invention as set forth in the following claims. 95

I claim:

1. In a roadway, a continuous concrete slab, thin metal plates set on edge embedded in the lower portion of the roadway and having their upper edges a distance below the 100 upper surface of the roadway, some of said plates extending longitudinally of the roadway and others extending cross-wise of the roadway, and reenforcing bars embedded in

the concrete parallel to and on both sides of said plates.

2. In a roadway, a continuous concrete slab, thin metal plates set on edge embedded in the lower portion of the roadway and having their upper edges a distance below the upper surface of the roadway, some of said

plates extending longitudinally of the roadway and others extending cross-wise of the roadway, and reinforcing bars embedded in the concrete parallel to and on both sides of said plates, and also along the outer edges of said slab. 10

BERNARD BRIODY.
